REVOLUTION COUNTER

Ralph G. Moody, United States Navy

Application October 2, 1933, Serial No. 691,979

4 Claims. (Cl. 235—104)

(Granted under the act of March 3, 1883, as
amended April 30, 1928; 370 O. G. 757)

This invention relates to a mechanism for counting the revolutions of rotating elements, such as shafts, and has for its object to provide a simple yet accurate means that will be of low cost, easy to manufacture and install, and unlikely to get out of order.

In the drawing:

Fig. 1 shows a side elevation of my invention with parts cut away, and a schematic diagram 10 of the electrical connections therefor:

Fig. 2 is a diametral section through the rotating parts of the counter mechanism.

The shaft 3 is mounted to be rotatable and is connected, preferably through suitable reducing 15 gears, to the element whereof the revolutions are to be counted. Within a housing 4 a disk 5 is mounted upon shaft 3 and is driven by the shaft through a key 6, a keyway 7 being provided in the hub of disk 5 to permit longitudinal sliding 20 of the disk 5 upon shaft 3. This disk has a laterally turned peripheral flange 8 whereof the edge is provided with teeth 9 adapted to engage teeth 10 on the edge of a like flange 11 on disk 12 that is freely rotatable on sleeve 13 carried by housing 25 4. A spring 14 is disposed between disks 5 and 12 and normally keeps them separated so that shaft 3 may rotate without driving disk 12. It is to be understood that shaft 3 may be provided with a clutch or other suitable mechanism for 30 disconnecting it from the rotating element. A helical spring 15 has one end secured to the sleeve 13 and the other end to a pin 16 fixed to disk 12 and is so wound that it tends to impart to the disk 12 rotation in a direction opposite to that of 35 shaft 3.

A drum 17 has an annular flange 18 that fits within a flange 19 on the housing 4, the periphery of drum 17 having inscribed thereon revolution-indicating numerals 20 that are visible through 40 a window 21 in housing 4. The coacting flanges 18 and 19 constitute the means for supporting drum 17 to permit rotation thereof. A plane helical spring 22 has one end secured to sleeve 13 and the other to the flange 18 and is so wound that it 45 tends to move the drum in a direction opposite to the rotation of shaft 3. A plurality of clips 23 secured to the housing 4 coact with a radially extending flange 24 on drum 17 to prevent lateral displacement of the drum. Lug 25 on disk 12 is 50 disposed to contact a lug 26 on drum 17 and so to form a positive driving connection between the disk and the drum when the disk is rotated in one direction, but to leave the drum free of the disk when the disk is rotated in the opposite direction. 55

Upon the periphery of flange 24 are ratchet

teeth 27 so directed as to permit rotation of the drum in the same direction as shaft 3, but to engage the bell crank pawl 28 and prevent rotation thereof in the opposite direction, the spring 29 being provided to hold the pawl in position 5 to engage teeth 27. A solenoid 30 is disposed to rock pawl 28 on its pivot and disengage it from teeth 27 at certain times as will be hereinafter set forth. A bell crank lever 50 is pivotally mounted with one arm disposed to be movable against the member 31 and push disk 5 over so the teeth 9 thereof engage the teeth 10 of disk 12, a solenoid 32 serving to rock the lever 50 and so move disk 5 as mentioned.

The clock mechanism diagrammatically represented by gears 33 drives the contact arm 34 at a predetermined speed. The contacting element 35 on arm 34 bridges the arcuate contact segments 36 and 37 and connects them together electrically, the said segments being in circuit with the solenoid 32. A second pair of contact segments 38 and 39 are connected together by the contacting element 40 on arm 34. It is to be noted that the segments 36 and 37 have an angular extent of substantially 270° while the segments 38 and 39 are about 60°, and that the arm 34 will move off the last-mentioned segments before it does off the first-mentioned segments.

The mode of operation is as follows: It is assumed that the shaft 3 is connected to the element whereof the revolutions are to be counted and that arm 34 is being driven by the mechanism 33. As soon as element 35 comes in contact with the segments 36 and 37, the direction of rotation of the arm being indicated by the arrow, 30 solenoid 32 will be energized and will rock the lever 50 which will slide disk 5 into driving engagement with disk 12. Through lugs 25 and 26 the drum 17 will be rotated by disk 12 and will continue to rotate until arm 34 has passed completely over the segments 36 and 37. As soon as arm 34 passes off segments 36 and 37, the solenoid 32 will be de-energized and spring 14 will disengage disk 5 from disk 12, whereupon the spring 15 will rotate disk 12 back to its initial 40 position. The drum 17, however, will be held against reverse movement by pawl 28 and may be read through the window 21.

It is to be noted that during the first revolution of arm 34 the solenoid 30 will be energized 50 during the time that element 40 bridges the segments 38 and 39, but this bridging of segments 38 and 39 will have no effect since the drum is being positively driven by disk 12. However, during the next and subsequent revolutions 55

of arm 34, as soon as element 40 bridges segments 38 and 39, pawl 28 will be released from teeth 27 and spring 22 will move drum 17 back until the lug 26 on the drum meets lug 25 on disk 12 after which the drum will move forwardly with disk 12 until the disk again ceases to rotate. If the shaft 3 has slowed down it is apparent that the drum will not be driven as far around as it was the previous time and the reading will be lower; on the contrary, if shaft 3 has speeded up, the disk will be carried beyond its previous position before being stopped and the reading will be higher. Breaking the circuit through segments 38, 39 and solenoid 30 before the driving 15 of disk 12 is terminated through interrupting the circuit that includes segments 36 and 37, insures that pawl 28 will be operative to lock drum 17 in the position it has when the disks disengage and so holds the drum stationary at 20 its maximum reading.

A stop 41 is provided to engage a lug 42 on disk 12 and arrest the reverse movement of the disk at the proper place. If desired, lugs 25 and 26 may have their contacting faces coated with some 25 substance of low elasticity, such as lead, wood or rubber, or they may have blocks of such material set into them, to prevent excessive rebound and shock when the drum moves back into driving engagement with the disk. The rate of revolution of arm 34 should, with the construction shown, be so adjusted to the rate of shaft 3 that the disk 12 will not be driven a full revolution during one timing interval at the maximum speed of the rotating element to which the device is connected. If disk 12 should be driven more than 30 one revolution there would be danger of breaking spring 15. The numerals 20 on drum 17 should be continuous from one to the maximum number of revolutions per unit time executed by 35 the rotating element to which shaft 3 is connected. A convenient time interval for one revolution of arm 34 is four seconds, which will give at least one second out of each four during 40 which the drum 17 will be stationary and can be easily read.

The invention described herein may be manufactured and used by or for the Government of the United States of America for governmental purposes, without the payment of any royalties 50 thereon.

I claim:

1. A revolution counter, comprising a shaft drivable at a rate having known relation to the rate of the shaft whereof the revolutions are to 55 be counted, a first disk mounted thereon to rotate therewith but to be slidably longitudinally thereof, said disk having a laterally turned peripheral flange with teeth on the edge thereof, a second disk rotatably mounted on said shaft, 60 said second disk having a laterally turned peripheral flange with teeth engageable with the teeth on the first disk and a laterally projecting lug on the side thereof opposite said flange, a spring between said disks tending to separate 65 them, a plane helical spring connected to said second disk to move it in the direction opposite to the rotation of the first disk; a rotatable drum having revolution indicating marks on its periphery, ratchet teeth on the periphery of the 70 drum so directed as to permit rotation thereof in the direction of rotation of said shaft and having a lug engageable by the lug on said second disk; a plane helical spring connected to said drum to rotate it in the direction opposite 75 to the rotation of said shaft, means to engage

said ratchet teeth to lock said drum against being rotated by said helical spring, means to move said first disk periodically into engagement with said second disk for a predetermined interval, and means to release said locking means during each period of engagement of said disks, said interval of release of the locking means being much less than the said period of engagement and terminating shortly before the termination of said engagement. 10

2. A revolution counter, comprising a rotatable shaft, a first disk feathered thereon to slide longitudinally thereof, a second disk rotatably mounted on said shaft, said disks having interengageable portions, a lug on said second disk extending oppositely to the said interengaging portion thereon, a spring between said disks tending to separate them, means normally tending to move said second disk opposite to the direction of rotation of said shaft; a rotatable drum coaxial with said disks having revolution indicating marks on its periphery, ratchet teeth on its periphery so directed as to permit rotation thereof in the direction of rotation of said shaft and having a lug engageable with the lug on said second disk, means to rotate the drum in the direction opposite to the rotation of said shaft, means normally locking said drum against rotation in said opposite direction, a first electrically actuatable means to release said locking means, means to slide said first disk longitudinally of said shaft into engagement with said second disk, a second electrically actuatable means to operate the last previously mentioned means, and time-controlled means to govern the energization of both of said electrically actuatable means, the time of actuation of the second electrically actuatable means beginning much earlier and ending somewhat later than the time of actuation of the first electrically actuatable means. 20

3. A revolution counter, comprising a rotatable member having on it indicia, means to rotate said member in one direction, means to lock said member against movement in the opposite direction, means tending to move said member in said opposite direction; means to control the rotation of said member in said one direction including a solenoid, a pair of spaced concentric conducting members respectively connected to the terminals of said solenoid, a rotatable arm pivotally mounted at the center of curvature of said conducting members, a conducting element on said arm contactable with said conducting members to close the circuit through said solenoid, horological means to drive said arm; a second pair of spaced 55 conducting members concentric with each other and with the aforesaid pair, a second conducting element on said arm to contact the members of said second pair, and a solenoid having its terminals respectively connected to the members of said second pair and disposed to unlock said locking means when energized, the angular extent of said second pair being small in comparison with that of the first pair and the termini of said second pair being disposed to be reached by said arm before those of the first pair. 60

4. A revolution counter, comprising a rotatable shaft, an indicating drum rotatable thereon and provided with ratchet teeth on its periphery, means to drive said drum including a member rotatable with said shaft but slidably longitudinally thereon, a bell-crank pawl mounted to have one end engageable with said ratchet teeth, a spring to hold said end in contact with said 70

ratchet teeth, a first solenoid to move said pawl out of engagement with said ratchet teeth, a bell-crank lever having one arm disposed to be movable against said member to slide said member and thereby effect a driving connection between said member and said drum, a second solenoid disposed to act on the other arm of said lever so to move said one arm, a pair of concentric contact elements in the form of a major circular segment respectively connected to the terminals of said second solenoid, another pair of contact elements

in the form of a minor circular segment adjacent the first mentioned segments but terminating short of the termini of the first said segments respectively connected to the terminals of the first solenoid, a rotatable arm mounted at the common center of all of said segments and having a circuit-closing contact element electrically connecting together the elements of the first said pair and a like element to connect together the elements of said other pair of contact elements. 5 10
